ADJUSTABLE BED

Finn Andre Kjellberg, Bent Ivan Kjellberg, and Sven
Edward Nielsen Lemvig, all of 13 Ostergade, 3700
Ronne, Denmark

Filed Feb. 2, 1970, Ser. No. 21,218

Claims priority, application Denmark Aug. 4, 1969

Term of patent 14 years

Int. Cl. D6—01

U.S. Cl. D5—4

Fig. 1.

Fig. 2.

Fig. 3.

Fig. 4.

Fig. 5

Fig. 6.

FIG. 1 is a side elevational view of an adjustable bed, showing our new design in elevated position, the opposite side being substantially a mirror image thereof;

FIG. 2 is an end elevational view in elevated position, the opposite end being substantially a mirror image thereof;

FIG. 3 is a top plan view, the articulated bed top being omitted for convenience in illustration;

FIG. 4 is a fragmentary side elevational view in lowered position, a portion of the side and an end board being broken away and omitted for convenience in illustration;

FIG. 5 is a side elevational view in elevated position, showing the articulated bed top in an adjusted position; and

FIG. 6 is a perspective view thereof in elevated position, the articulated bed top being omitted for convenience in illustration.

We claim:

The ornamental design for an adjustable bed, as shown and described.
